UNITED STATES PATENT OFFICE.

WILLIAM B. SMITH WHALEY, OF MELDEN, MASSACHUSETTS, ASSIGNOR TO AMERICAN WHALEY ENGINE COMPANY, OF BOSTON, MASSACHUSETTS, A CORPORATION OF MASSACHUSETTS.

AUTOMATIC SAFETY VALVE.

Application filed December 5, 1917. Serial No. 205,706.

To all whom it may concern:

Be it known that I, WILLIAM B. SMITH WHALEY, a citizen of the United States of America, and resident of Malden, in the county of Middlesex and State of Massachusetts, have invented a new and useful Automatic Safety Valve, of which the following is a specification.

This invention relates to an automatic safety valve adapted more particularly for automatically scavenging and regulating the air pressure in air tanks and to prevent pocketing of the air therein. This is particularly the case where said tank has a single or common inlet and outlet or intake and discharge means. The air delivered by the pump to a storage pressure tank always contains entrained particles of lubricating oil which, by reason of a lack of circulating means, pockets at points beyond the said common inlet and outlet; that is, the oil collects at the lowest point in the tank with pocketed or unliberated air, and carbureted air results, which is a source of extreme danger. This, together with the static electricity provided by the friction of the air against the metal of the tank, is one of the most common causes of explosions of air tanks. Scavenging the tank of oil or oil vapors is therefore most important, and this invention is designed to accomplish scavenging by the delivery of the air to the top of the tank and removing the air from the bottom of the tank where pocketing is most likely to take place. This is done by a single valve which also automatically tends to maintain a constant pressure within the tank. Certain other features and advantages in connection with the use, application or operation of the invention will be pointed out in the description hereinafter.

In order to illustrate my invention, I have shown in the accompanying drawing one embodiment thereof, wherein: Fig. 1 illustrates an elevation partly broken away, of a storage tank or receptacle with a valve of my invention applied thereto and cooperating with air or gas supply means and utilization means illustrated diagrammatically.

Fig. 2 is an enlarged central vertical section through a valve of my invention.

The terms employed herein are used in the generic and descriptive sense to desig-

nate elements, and are not therefore intended as terms of limitation of the invention.

Herein for example, 10 represents the closed storage tank or closed container for air, gas or the like, whether portable or stationary. The top head 11 thereof is provided with an opening 12 surrounding which and bolted at 13 to the edges of the head is the flange 15 of the valve body 16. Said valve body 16 may be of any preferred design or shape best adapted to have embodied therein the elements and operating mechanisms adapted to carry out the principles and objects of said invention. To facilitate the construction of the device, the top of said body 16 has an opening at 17 and closing the same is a head 18 secured thereto by the bolts 19. Within the said body 16 is the enclosing cylindrical wall 22 to form a central chamber 23 having leading thereto a conduit 24 in communication therewith. Said chamber and conduit 24 are common to both the inlet and outlet of air as described herein-after. Leading from said chamber 23 is an outlet port 25 preferably surrounded by a valve seat 26 and communicating with the conduit 28 between the body 16 and wall 22. The conduit 28 communicates directly with the interior of the tank 10 through the opening 12 at the top thereof.

The port 25 is normally closed by the valve 30 engaging the valve seat 36. Said valve is preferably held to said seat by a spring 31 surrounding the tubular valve stem 32, preferably integral with the valve and slidable in the bore 33 within the extension 34 projecting centrally of the head 18. The said spring 31 engages and is compressed between the top surface of said valve 30 and the lower face of the head 18.

From a position close to the bottom of the tank 10 the open end of an extended conduit 35 leads upwardly through the tank and is fastened into the boss of the discharge port 37 communicating with the chamber 23. Inferiorly of the said chamber 23 the discharge port 37 is surrounded by the valve seat 38. Said discharge port is normally closed by the valve 40 in contact with said valve seat 38. Centrally of said valve, and preferably integral therewith, is a valve stem 41 preferably guided in the bore 42 in the tubular valve stem 32. Surrounding said valve stem 41 and bearing on the top surface of the

valve 40 and the under surface of the valve 30 is a spring 44 adapted normally to hold said valve 40 to its valve seat 38.

The exposed area of the upper surface of the valve 40 is equal to the area of the valve 30 likewise exposed within the chamber 23. The area of the lower face of the valve 40 exposed to the interior of the tank 10 and the pressure therein, is of less diameter than the area of the upper surface of the valve 30 exposed to the pressure interiorly of the said tank. It is also pointed out that the compression value of the spring 44 is half that of the spring 31. For example, the spring 44 may be termed for convenience a five pound spring under compression as compared to the spring 31 termed a ten pound spring.

The conduit 24 being common to both intake and discharge of air from said tank, the said conduit is preferably connected to an air compressor or an air pump 45 herein illustrated as a double acting pump. Said connection is made by means of the pipes 46 and 47 joined to the said conduit 24 which is continued herein to the regulating valve 49 and to the engine or prime mover 50.

The air compressor 45 is provided with the usual inlet 51 and check valves 52. Said air pump is preferably coupled to or operated by the engine illustrated, and is adapted to maintain, as near as it is possible to do so, a constant volume of air at a substantial constant pressure. The prime mover 35 or engine illustrated is of the internal combustion engine type, preferably having a positively actuated valve adapted to permit of the admission of air to a reservoir of the engine and from there drawn into the engine through a poppet valve during the suction stroke. The engine in part illustrated is of the retarded combustion type, wherein air is admitted late in the cycle of combustion to complete the same.

It will be understood, however, that any other type of prime mover may be utilized in connection with the invention, as for example, other internal combustion engines, compressed air motors or air operated tools and implements. Therefore, a large volume reservoir or tank is desirable and the valve has its particular application to such tank.

The operation of the invention is as follows:

The air is compressed by the pump 45 and flows through the conduits 46 and 47 at each alternate stroke of the piston in the pump. The air is conducted through the conduit 24 into the chamber 23 in the valve. The valve 40 is maintained in contact with its seat both by reason of the pressure upon the top surface thereof and by the assistance of the spring 44. The valve 30, however, is caused to move from its seat 26 permitting the air 65 to pass through the port 25 into the con-

duit 28, thence through the opening 12 into the tank 10. Attention is again directed to the fact that this entering air is delivered at the top of the tank and cannot return through the port 25 and pass the valve 30 but must flow to the bottom of the tank and pass upwardly through the conduit 35.

The pump continues to operate and compress and force into the conduit new air, and if the air pressure within the tank is less than that flowing through or maintained in the conduit 24 the valve 30 will move from its seat until such time as the two pressures will become equal. Now, if during the course of the operation of the prime mover, more air is required thereby, as for starting purposes, or the pressure in the conduit 24 becomes less than that in said tank as when the air pump is shut off and the conduit 24 is open to the prime mover or engine 50 during the end of the piston stroke when the pressure in the cylinder is low or when the conduit 24 is open to the cylinder during exhaust, air will pass up through the conduit 35 to the port 37 causing the valve 40 to recede from its seat permitting the compressed air to flow into the said conduit 24 and therealong to the prime mover 50 until such time as the pressure of the air within said conduit exceeds that within the tank.

The valve 40 will then reseat itself and during the next few strokes of the engine the valve 30 will tend to recede from its seat 26, permitting air to again enter the conduit 24 thence to the tank 10 to restore the pressure therein to the maximum pressure.

As lubricating oil from the compressor or pump 45 is being constantly entrained in the air and must necessarily find its way into the tank 10, it is always directed by the flow of the air to the bottom of the tank where it is drawn up through the conduit 35 and port 37 past the valve 40 to the conduit 24 where it will flow therealong to the prime mover 50 where it will be taken up in the combustion cycle or operation of the engine. Therefore, no substantial quantity of oil can become entrained or deposited within the tank 10 to induce sufficient carbureted air therein to be dangerous.

The friction resulting from the flow of air through a metal container or conduit frequently causes a static charge of electricity upon the metal, which is a constant source of danger. A sudden change of the static condition, either by some unforeseen premature or accidental grounding of some part of the metal or change of electrical capacity thereof, will cause a spark to arc between the metal parts interiorly of the container. If no appreciable amount of carbureted air is present, no dangerous effect can be had. On the other hand, a properly proportioned mixture of carbureted air within the container will be

fired by the discharge of the static charge of electricity, and thereby cause combustion resulting in the bursting of the container. These are conditions frequently met with 5 where said container or tank has but a single inlet and discharge orifice, valve, valve conduit, or the like. By reason of the use of a valve of my invention, the air is delivered at one portion of the tank and 10 discharged at another portion to eventually repass through the same valve and maintain a constant circulation thereof. Therefore, the dangerous conditions above referred to cannot occur, and likewise, the valve tends 15 automatically to control the inlet and discharge of air to the container with constant circulation thereof and to maintain the air at practically constant pressure.

This valve may be utilized in connection 20 with any tank designed for a storage of compressed air, gas or the like, employing but a single inlet and outlet member, as for example, portable tanks, carbonous gas tanks utilized for the manufacture of 25 beverages, tanks for the storage of air for the operation of air operated tools or machinery, or tanks adapted to hold an illuminating gas or the like. Many other applications may be readily understood by those 30 skilled in the art and the advantages of a valve of the principles set forth herein, when supplied thereto, will be readily appreciated.

No check valves or adjusting features are required by the use and application of said 35 valve. Likewise, there cannot be any invitation to tamper with the same to change its operation and control of the air passing therethrough. There is no provision for regulating means as the valve is entirely 40 automatic in its operation and control of the air, gas or the like.

I have described herein one embodiment of my invention, but it is to be understood that the latter is not essentially limited to 45 the specific construction and organization of said embodiment, since the same may be varied without departing from the proper scope of the claims.

The term gas in the specification and 50 claims includes any elastic fluid or medium.

Having thus described my invention in detail, what I claim as new is:

1. The combination of a tank having an opening and an extended conduit therein 55 and a valve comprising a casing, a wall therein to provide an interior chamber, said casing and wall being spaced to form a conduit therebetween adapted to communicate with the interior of said tank through said 60 opening, said wall having a plurality of ports therethrough in communication with the said chamber, one of said ports being in communication with said last mentioned conduit and the other port communicating 65 with said extended conduit projecting to a

distant portion of the said tank, a valve for each port, and means communicating with the interior of said chamber to permit the passage of a gas to and from said chamber.

2. In a valve, a casing, a wall therein to 70 provide an interior chamber and a conduit between the casing and wall, said wall being provided with a port surrounded by a valve seat and communicating with said conduit, an extended conduit having an opening distant from the first mentioned conduit and communicating with the interior chamber through a port surrounded by a valve seat, a valve normally engaging each valve seat to close each port and a common intake and 75 discharge conduit in communication with said interior chamber.

3. In a valve, a casing, a wall therein to 80 provide an interior chamber and a conduit between the casing and wall, said wall being provided with a port surrounded by a valve seat and communicating with said conduit, an extended conduit having an opening distant from the first mentioned conduit and 85 communicating with the interior chamber through a port surrounded by a valve seat, a valve normally engaging each valve seat to close each port, a common intake and discharge conduit in communication with said interior chamber, and springs adapted to 90 maintain said valves on their respective seats.

4. In combination with a tank, a valve having a casing provided with means for directing a compressed gas to one end of 100 said tank and for withdrawing said compressed gas from a distant end of said tank, a common gas intake and discharge means for said casing and valve mechanisms adapted to control the flow of gas between said 105 common intake and discharge and the said directing means and the said withdrawing means.

5. In combination with a tank, a valve having a casing provided with conduit 110 means for delivering compressed gas to said tank at a point adjacent to the casing and provided also with an extended conduit projecting within said tank for withdrawing the said gas from said tank at a point distant from said delivery means, a common gas intake and discharge means for said casing, and one way valve mechanisms adapted to permit the passage of a gas from the said 115 common intake and discharge to the delivery means and to permit withdrawal of gas from said extended conduit to the said common intake and discharge.

6. In combination with a tank, a valve having a casing, means within said casing 120 for delivering a gas to said tank at a point adjacent to the casing and for withdrawing the gas from said tank at a point distant from said delivery means, said casing having a common intake and discharge means 125 130

for a gas, and valve mechanism in said casing controlling the direction of flow from said common intake and discharge means to said delivery means and for controlling 5 the direction of flow from the withdrawal means to the said common intake and discharge.

7. In a scavenging valve apparatus, a storage tank, a single valve mechanism for 10 said tank controlling both the intake and withdrawal of a gas therefrom, said valve comprising a casing having means for delivering a gas to the interior of the tank at the top and means extended to the bottom 15 of said tank for the withdrawal of the gas therefrom, means for delivering a gas to and from said casing and adapted to be connected to the source of gas supply and to means to the interior of the tank, and for 20 utilizing the said gas and a valve mechanism in said casing adapted to direct the flow of said gas from said delivery means to direct the flow of said gas from the lower withdrawal means to the discharge means.

8. In a valve, a casing having a central 25 chamber, a valve within said chamber for admitting a gas thereto, a valve exterior to said chamber for delivering a gas therefrom, and means communicating with said valves for delivering a gas from said chamber and 30 admitting a gas thereto at points distant one from the other.

9. In a valve, a casing having a chamber therein provided with a set of valve ports 35 communicating therewith and surrounded by valve seats, a pair of adjacent valves movable in the same direction to uncover said seats surrounding said ports communicating with said chamber for admitting and delivering a gas to and from said chamber 40 at points distant one from the other, and means for admitting a gas to said chamber from a source of supply.

WILLIAM B. SMITH WHALEY.
